Fig. 3

A diagram showing a rectangular frame with a coiled spring inside. The corners of the frame are labeled 173. The top edge of the frame is labeled 177. The bottom edge of the frame is labeled 179. The top right corner of the frame is labeled 175. The coiled spring is positioned within the frame.

A diagram of a rectangular component with several labeled parts. At the top left is a vertical line labeled '167'. At the top center is a horizontal line labeled '45'. At the top right is a horizontal line labeled '171' and '169'. Along the bottom edge, there are two vertical lines labeled '173' and '171' respectively. The component has a central vertical slot and a small rectangular protrusion on the left side.

Fig. 1 shows a rectangular frame structure with the following dimensions:

- Top horizontal side: 33, 23
- Left vertical side: 23, 29, 31
- Right vertical side: 37, 39, 25
- Bottom horizontal side: 43, 181, 25, 35
- Bottom left corner: 169

TOY MATERIAL HANDLING AND DISPLAY
DEVICE

Russel D. Beerbower, Fort Wayne, Ind.

Application August 9, 1939, Serial No. 289,159

13 Claims. (Cl. 46—40)

This invention relates to a mechanism for conveying from place to place and for classifying objects. More specifically it relates to a toy which is adapted to receive an assortment of attractive objects such as colored marbles, elevate them and classify them for delivery to a vehicle or other station at a lower elevation.

One of the objects of my invention is to provide a conveyor which is driven from a central power source but which may be pivoted to any desired degree while being driven.

Another object of my invention is to provide a classifying system which comprises a receiving bay, a feeder device and a classifying device.

Yet another object of my invention is to provide a classifying system in which the objects to be classified may be circulated to afford amusement.

Still another object of my invention is to provide an object feeding device which may receive a number of objects but which will discharge them singly and at regular intervals.

Still another object of the invention is to produce a conveying system which may be conveniently used with other well known toys such as dump trucks, trains, wagons, etc.

Another object of the invention is to provide means for selectively returning classified objects from the containers receiving them to the conveyor system.

Other objects will become apparent from a consideration of the following specification and the drawings which form a part thereof and in which:

Figure 1 is a plan view showing the conveyors, feeding device, classifier, power system and the various receptacles appurtenant thereto.

Figure 2 is an end elevation of the device of Figure 1, but with the conveyor rotated ninety degrees and elevated.

Figure 3 is a sectional view taken on the line 3—3 of Figure 2 showing the frame structure of the device as well as the method of mounting various parts.

Figure 4 is an end elevation of the feeding device viewed from the left of Figure 2.

Figure 5 is a side elevation of the device of Figure 4.

Figure 6 is a plan view of the chute showing the telescopic point and the chute support.

Figure 7 is an end view of the device of Figure 6.

Figure 8 is a section view taken on the line 8—8 of Figure 1.

Referring to Figures 1, 2, and 3, the numeral 1

represents a base to which are fixed two side brackets 3 by means of bolts 5 which pass through flanges 7. Ears 9 are also formed on the brackets and are turned inwardly to receive a U-shaped channel 11. Bolts 13 pass through the channel, ear, flange 7 and base 1 to hold all of said parts in position.

The brackets are provided with projecting portions 15 which extend beyond the base so that cars or trucks may be loaded by gravity from the hoppers or compartments to be described. These portions of the brackets are provided with inwardly directed flanges 17 and 19 at their upper and lower edges respectively. Extending between 15 and fixed to these flanges by bolts 21 are two angular strips 23 and 25 which form a tube of rectangular cross-section (see Figure 3) with the legs of the angles forming the walls thereof. Walls 25 are formed with tabs or projections 24 as shown in Figure 3, which enter slots in the walls 23 and are bent over or twisted to hold the walls in close relation.

A partition 27 is placed across said tube and is held in place by tabs which extend through the walls thereof to form two compartments A and B (Figure 1). A second partition 28 completes the compartment A.

Two openings 29 are formed in the front wall 23 of the tube and adjacent the bottom thereof, 30 one of which communicates with hopper A and the other with hopper B. A loop 31 (Figure 8) is pressed inwardly above each of the openings and slideable gates 33 are mounted in the loops to close the openings.

Two openings 35 are also formed in the bottom portion 25 of the tube one communicating with each of the hoppers (Figures 1 and 8) and these openings are closed by gates 37 which are slideable in loops 39 formed in the back wall of the tube and which have bent over portions 41 adapted to close the openings when the gates are in their lowermost positions.

A short chute 43 (Figures 1 and 8) is formed on the lower wall 25 adjacent openings 29 and is adapted to receive objects discharging from either opening. This chute tapers at its outer end so as to discharge one object at a time into the trough 45 to be described.

Two vertical columns 47 of U-shaped cross-section extend between the tube and the base 1 (Figures 2 and 3). These columns are provided with flat projections 49 at their upper ends which are slidably received in loops 51 pressed out of the front wall 23 of the tube and with projec-

tions 53 at their lower ends which enter slots formed in the base 1.

Ears 55 are bent up from the channel member 11 to form bearings for the power shafts 57 and 59 the other ends of which are supported in holes formed in the columns 47.

Pulleys 61, 63 and 65 are mounted on shaft 57 while pulleys 66 and 67 are fixed to shaft 59. A suitable belt connects pulley 67 with that of an electric motor 69 which is suitably fixed to the base 1. A belt connects pulleys 66 and 63 so that movement will be transmitted to shaft 57.

A shaft 71 is mounted in ears 73 which are pressed out of the base 1, and this shaft carries a pulley 75 which is connected by a belt with pulley 61 on shaft 57.

A substantially U-shaped pulley bracket 77 is adapted to support a shaft 79 upon which is mounted a two step pulley 81, 83. The bracket is provided with a projection 85 which is received in loops 87 formed from the upper side 23 of the tube described above. A belt connects pulley 65 with pulley 81.

Mounted above and upon the rectangular tube are two complementary brackets 89 which are provided with downwardly depending ears 91 which are perforated to receive a shaft 93. A feeder cylinder or drum 95 is provided with heads 97 and 99 which are perforated to receive the shaft.

The head 97 is cut away at 101 to permit objects to enter the cylinder while the head 99 is cut along the lines 103 and bent inwardly on the line 105 to form an inwardly extending finger 107.

A hopper 109 formed with an inclined bottom 111 is mounted adjacent the head 99 and is arranged to feed objects therethrough into the cylinder. The hopper is preferably mounted on an inverted U-shaped support 110 which is mounted on the top wall 23 by means of tabs 112 which pass thru slots in said wall and are bent over. The hopper is similarly mounted on the support by means of tabs 114.

A classifying track 113 is mounted above hoppers A and B and is provided with a trough 115 which is disposed adjacent the head 99 and is adapted to receive the objects discharged from the cylinder. The inner end of the track is supported on a collar 114 which rests on wall 23 and is held in place by means of a bolt 116. The outer end of the track is inserted between the top wall 23 and the bracket flange 17 and is held in place by bolt 21. The cylinder is tilted to feed objects toward the trough and classifier and the latter is tilted to feed the objects away from the cylinder. The track is provided with a slot 117 of predetermined width above the hopper A and with a slot 119 of greater width above the hopper B.

A belt runs from the pulley 83 around the cylinder 95 and serves to rotate the cylinder about its axis 93.

A hopper 121 is formed with an inclined bottom 123 and with an ear or projection 125 which is perforated to receive a vertical shaft 127. The shaft is mounted in a bearing 129 formed as a headed bushing which extends through the base 1 and is held in place by nut 128. The shaft carries a worm wheel 130 at its lower end and a miter gear 132 at its upper end (Figures 1 and 2). The wheel is driven by a worm 134 on shaft 74.

The hopper is provided with a substantially tangential trough 131 which is formed with rela-

tively high side walls 133 which are perforated to receive a horizontal shaft 135.

A conveyor indicated generally by numeral 137 is formed of a long flat member 139 which has its lateral edges bent upwardly to form the sides 141 of a trough and which has the center portion centrally slotted and bent downwardly into the plane of said sides 141, at each end as shown at 143.

A shaft 145 extends through perforations in the upper end portions 143 and a roll 147 is mounted for rotation thereon. A roll 149 is mounted to rotate with shaft 135 which is driven by a miter gear 151 which is fixed thereto and which meshes with gear 132.

A belt 153 of any desirable flexible material runs over the rolls 147 and 149 and is provided with transversely extending cleats 155 adapted to engage under objects in the trough and to carry them upwardly with the belt as it is driven.

Numeral 157 indicates a post which is fixed to the side wall of the hopper 121 and which is provided at its upper end with two parallel spring ears 159 which are formed by slotting the tube and flattening the walls thereof. A cord 161 which is fixed to the conveyor frame, passes between and is frictionally held by said ears so as to hold the conveyor frame in any selected position.

If the conveyor is used for loading containers other than the hopper 109, an auxiliary chute 163 having ears 165 adapted to fit over the ends of axle 145 may be used as shown in Figure 2.

The extensible trough 45 is formed substantially semi-circular in cross-section and of two parts 167, 169, the former part being larger than and adapted to receive the latter. Two ears 171 on 167 are bent over as shown in Figure 6 to engage the inner surface of 169 to hold the chutes in position.

A standard 173 of U-shaped cross-section is held in place on the base 1 by a bolt 175. The standard is provided with an opening 177 adapted to receive the trough sections. The opening is provided with shoulders 179 which serve to hold the troughs in position.

Standard 173 is so placed as to direct the trough between the chute 43 and the hopper 121. The end of the trough 45 adjacent chute 43 is provided with a projection 181 which passes through the front wall 23 as shown in Figure 3 and is bent downwardly to hold the chute in place.

An inclined way 183 shown in Figure 1 may be used to facilitate the rolling of trucks or other vehicles up to a position in which they may be emptied into the hopper 121. The way may be provided with flanges 185 to guide the wheels of the vehicles.

Operation

With the motor running, the conveyor is set in motion in a direction to elevate objects, it being driven by the gearing 59, 67, 66, 63, 61, 75, 71, 134, 130, 127, 132, 151, 135, and roll 149. It serves to elevate the objects which are preferably balls or marbles and discharge them into the hopper 109. The cleats 155 are wide enough to lift two balls at a time and hence the latter accumulate in the hopper.

The cylinder 95 is rotated by the motor by means of the gearing 59, 67, 66, 63, 57, 65, 81, and 83.

The belt on pulley 83 runs entirely around the cylinder and rotates it in the direction indicated by the arrow in Figure 4, with the result that balls which are fed into the cylinder through

openings 101 due to the sloping bottom of the hopper are fed by the inclined position of the drum into engagement with the head 99 thereof and are picked up by the finger 107 and discharged into trough 115 and on to the classifier 113. The space between the head 99 and the tip of the finger 107 is sufficient to permit the passage of only one ball hence only one ball is discharged by the drum in each revolution.

As indicated above, the balls are preferably of different sizes and each size is distinctively colored. As the balls roll down the inclined classifier 113, the small balls will drop through slot 117 and into hopper A which will accordingly contain balls of one color, while the large balls will pass over slot 117 and drop through slot 119 into hopper B which will therefore collect balls of another color.

It is of course obvious that any suitable number of ball sizes, colors and hoppers may be provided instead of the two herein disclosed if this is desired.

The balls may be discharged from hoppers A and B into vehicles or containers placed under the hoppers through the bottom openings 35 by raising the gates 37. Alternatively they may be discharged through the front openings 29 when the front gates 33 are raised. In this case they will run out through chute 43 and troughs 169 and 167 into the conveyor hopper 121 where the cycle may begin again making a continuously operating device.

If the conveyor is directed into a different container and the trough 167 is adjusted to discharge into the hopper 121, such container may be loaded from the previously charged hoppers A and/or B as desired. The height and inclination of the conveyor may be adjusted manually to suit conditions and the position will be maintained by the friction member 159 acting on the cord 161. The attachment 163 is removable and is used when the elevation of the conveyor is such as to require a lateral displacement of the balls beyond the conveyor proper.

Vehicles may be run up the track 183 on to the base 1 and emptied into the hopper 121. The track is movable so that it may be placed to suit the requirements.

The conveyor and hopper may be pivoted for the full 360 degrees about shaft 127 and it will operate in any such position. In some positions it will be impossible to fill the hopper 121 from trough 45 since the hopper will pass beyond the range of the trough.

It is obvious that various changes can be made in the form, construction and arrangement of parts without departing from the spirit of the invention. Applicant does not therefore desire to be limited to the specific embodiment herein disclosed as the preferred embodiment of his invention but rather he desires protection falling fairly within the scope of the appended claims.

What I consider to be new and desire to protect by Letters Patent of the United States of America is:

1. In a ball handling toy, the combination of first and second hoppers disposed at different levels and means for conveying balls from the lower to the upper hopper, a plurality of storage hoppers disposed at a level intermediate said first mentioned hoppers and means for gravitationally feeding said balls to said storage hoppers, said last named means including means

for automatically classifying said balls as to size and depositing all balls of similar size in the same hopper, means for feeding said balls one at a time to said classifying means and common power means for driving said conveying and said feeding means.

2. In a ball handling toy, the combination of a first hopper and a plurality of storage hoppers disposed at a level below said first hopper, a classifying device disposed above said storage hoppers and adapted to distribute said balls according to size to said storage hoppers, and means for releasing balls singly to said classifying element, said means comprising an element mounted for rotation about an axis and having an eccentric opening therein, a baffle mounted to overlie said opening but spaced therefrom to permit lateral entrance of a ball therebetween and means for rotating said element whereby one ball will pass around said baffle and through said opening at each revolution of the element.

3. In a ball handling toy, the combination of a first hopper and a plurality of storage hoppers disposed at a level below said first hopper, a classifying device disposed above said storage hoppers and adapted to distribute said balls according to size to said storage hoppers and a ball releasing device comprising a receiving compartment mounted for rotation about an axis and provided with a head disposed transversely to the axis of rotation, said axis being inclined downwardly in the direction of said head, an opening disposed eccentrically of said head, and a baffle disposed transversely of said axis and spaced axially inwardly over said opening a distance less than a multiple of the diameter of a minimum sized ball, and means for rotating said compartment, head and baffle as a unit about said axis in a direction to entrap a ball, which gravitates toward said head, between said head and said baffle.

4. In a ball handling toy, the combination of first and second hoppers disposed at different levels and means for conveying balls from the first to the second hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, selectively controllable discharge openings on said storage hoppers and additional means disposed between the openings in said storage hoppers and said first hopper for conveying balls from the former to the latter.

5. In a ball handling toy, the combination of first and second hoppers disposed at different levels and means for conveying balls from the first to the second hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper said conveyor being mounted for rotation about a vertical axis to permit delivery by the conveyor to selected points in a horizontal plane, selectively controllable discharge openings in said storage hoppers and additional means for conveying balls from said openings in said storage hoppers to said first hopper.

6. In a ball handling toy, the combination of first and second hoppers disposed at different levels and means for conveying balls from the first to the second hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, said conveyor being mounted for rotation about a vertical axis to permit delivery by the conveyor to selected points in a horizontal plane, selectively controllable discharge openings in said storage hoppers and additional means for conveying balls from said openings to said first hopper said additional conveying means comprising an extensible member to permit adjustment of length to correspond with the position occupied by said first hopper.

7. In a ball handling toy, the combination of first and second hoppers disposed at different levels and means for conveying balls from the first to the second hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, selectively controllable discharge openings in said storage hoppers and additional means for returning balls discharged through said openings into said first hopper.

8. In a ball handling toy, the combination of first and second hoppers disposed at different levels and means for conveying balls from the lower to the upper hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, said conveyor being mounted for rotation about a vertical power driven shaft, to permit delivery by the conveyor to points in a horizontal plane, and means for connecting said conveying means to be driven by said power shaft.

9. In a ball handling toy, the combination of a first hopper and a plurality of storage hoppers disposed at a level below said first hopper, a classifying device disposed above said storage hoppers, and adapted to distribute said balls according to size to said storage hopper, and means for releasing balls singly to said classifying device comprising a cylinder provided with heads, means for mounting said cylinder for rotation about an axis, a discharge opening in the one head, gate means disposed adjacent said opening and adapted to permit passage of a ball

to said opening upon each revolution of said cylinder.

10. In a ball handling toy, the combination of first and second hoppers disposed at different levels and means for conveying balls from the lower to the upper hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, means for supporting said storage hoppers, comprising a base, bracket members provided with projections extending laterally beyond the base, said storage hoppers being supported by said projections, and means forming discharge openings in the bottoms of said storage hoppers, and selectively operable closures for said openings.

11. In a toy ball handling device the combination of a base, a pair of parallel and complementary brackets comprising inwardly directed parallel flanges, a pair of angle members fastened one to each pair of flanges to form a closed rectangular tube extending between said brackets.

12. In a toy ball handling device the combination of a base, a pair of parallel and complementary brackets comprising inwardly directed parallel flanges, a pair of angle members fastened one to each pair of flanges to form a closed rectangular tube extending between said brackets, columns formed of U-shaped cross-section and provided with flat projections on each end, loops pressed from one vertical wall of said tube and a slot in said base adapted to receive the respective projections, said tube being supported on the inwardly directed legs of said columns.

13. In a ball handling toy, the combination of first and second hoppers disposed at different levels and means for conveying balls from the first to the second hopper, a plurality of storage hoppers disposed at a level intermediate said first mentioned hoppers and means for gravitationally feeding said balls to said storage hoppers, said last named means including means for automatically classifying said balls as to size and depositing all balls of similar size in the same hopper, said conveyor being mounted for rotation about a vertical axis to permit delivery by the conveyor to selected points in a horizontal plane, selectively controllable discharge openings in said storage hoppers and additional means for conveying balls from said openings to said first hopper said additional conveying means comprising a ball guide, means for mounting said guide to discharge toward said first hopper, said guide comprising an adjustable portion at the discharge end thereof.

RUSSEL D. BEERBOWER.
